EYE EXERCISING DEVICE

Hugo Bermann, Jersey City, N. J.

Application July 2, 1940, Serial No. 343,643

2 Claims. (Cl. 128—76.5)

This invention relates to improvements in eye exercising devices and more particularly to a device to be used for eye calisthenics to develop and strengthen the muscles of the eyes.

It is generally known that weak eye muscles cause headaches and impair the nerve condition of the body. In order to correct the above defects and to correct any deficiencies in the development of the muscles of the eyes, it frequently becomes necessary to use or manipulate the eyes in a way to exercise these muscles or to practice special exercises to effect proper development of particular muscles.

Heretofore, the exercise generally prescribed by most eye doctors for exercising the muscles of the eyes at home is the well known pencil exercise. This exercise, however, requires a considerable amount of patience and tends to tire the arms of the patient, whereas the device of the present invention is relatively simple to use and is highly effective in producing the desired results.

Thus, the primary object of the present invention is to provide an efficient device for strengthening the eye muscles whereby to maintain them in condition to perform their proper functions and thus avoid defects in vision due to one or more of the muscles failing to properly coact with the other muscles.

A further object of the present invention is to provide an eye exerciser, the proper use of which will improve phorias, correct headaches and improve the general nerve condition of the body.

A still further object of the present invention is to provide a novel mechanical device, which is simple in construction, light, inexpensive to manufacture, capable of use with slight instruction, and adapted for effecting the exercises of the eye muscles in accordance with the main object of the present invention.

Other objects and advantages reside in certain novel features of the construction, arrangement and combination of parts which will be herein-after more fully described and particularly pointed out in the appended claims, reference being had to the accompanying drawing forming a part of this specification, and in which:

Figure 1 is a front elevation illustrating the device of my invention in use and as being actuated to move the fixation object toward and away from the eyes.

Figure 2 is a front elevation illustrating the device of my invention in use and as being actuated to move the fixation object to the right or left of the eyes.

Figure 3 is a section along the line 3—3 of Figure 2.

In carrying out my invention, I construct the main portion of the device of wire to enable same to be inexpensively manufactured although any other suitable material may be used. Referring to the drawing in detail, my device comprises a main body portion 4, wire frame generally indicated by the numeral 5, handles 6, 7, chin rests 8, 9, and a movable fixation object of spherical 10 form 10.

The frame 5 comprises a rectangularly shaped base member 11 formed of a single strand of wire and terminating in a chin rest 8. The width of the base portion is slightly less than the diameter 15 of the spherical object 10 for a purpose that will be apparent as the description progresses. The upper portion of the frame comprises a rectangularly shaped member 12 having downwardly turned portions forming vertical spacing legs 13, 20 14, the lower ends of which are welded or otherwise joined to base member 11. The height of the legs are slightly less than the diameter of the spherical object 10. A horizontal bar 15 joins the upper portions of legs 13 and 14 to prevent 25 separation of these legs. At the end adjacent the chin rest 8, vertical bars 16 and 17 are connected to members 11 and 12. The construction described above results in a wire frame of such size and proportion as to confine the spherical fixation 30 object within the space defined by the wire frame and at the same time permitting free movement of the spherical object from one end of the frame to the other by a mere tilting of the frame. The legs 13 and 14 and bars 16 and 17 function as end 35 stops for the spherical object. The handles 6 and 7 are provided for manipulation of the device and are welded or otherwise joined to the lower member 11 in such manner as not to interfere with the free movement of the spherical object. A 40 second chin rest 9 is joined to one side of the base member 11 at right angles thereto for a purpose to be more fully explained in the operation of the device. Although the chin rests are shown as being fixed to the frame member, it is to be understood that the same may be made adjustable in length to vary the distance between the frame member and the eyes. The spherical object 10 may be made of any suitable material but is preferably made of Celluloid and is of the size of 45 a ping pong ball.

In the normal operation of the device, the nature of the exercise desired will determine the movements to be imparted to the fixation object. Referring to Figure 1, either or both handles may 50

be grasped in the hand or hands and the chin rest 8 placed under the chin of the user. A slight tilting of the device in an up and down direction as indicated by the arrow will cause the spherical object to roll slowly down the trackway 5 formed in base member 11 toward and away from the eyes. The movement of the object closely followed by the eyes will exercise some of the muscles of the eyes thus improving their condition. For the exercise of additional muscles of 10 the eyes, the device is operated in the manner indicated in Figure 2. In this form of the operation, the chin rest 9 is used and the device tilted about the chin rest as an axis, causing the fixation object to move from a position to the right 15 or left of the eyes, with the eyes intently following the object at all times.

If the eyes should apparently be normal, they 20 may be improved and kept in good condition by the exercise of the eye muscles by frequent use of the present device, such exercise bringing all the muscles of the eyes into normal action and keeping them in condition to function properly, and if defects should exist which are subject 25 to correction by eye exercises, such defects may be remedied with the use of the present device.

Thus it will be seen that the construction herein shown and described is well adapted to accomplish the objects of the present invention. It

will be understood, however, that the invention may be embodied otherwise than here shown and that in the embodiment illustrated, certain changes in the construction may be made. Therefore, I do not wish to be limited precisely 5 to the construction herein shown except as may be required by the appended claims considered with reference to the prior art.

Having thus described my invention, what is claimed is:

1. A device for exercising the eyes comprising a frame member, said frame member defining an enclosed trackway, a spherical object on said trackway, said object being movable upon tilting of the trackway, handle means on said frame for 15 tilting the trackway, and a chin rest mounted on the frame member for holding the device spaced from the eyes.

2. A device for exercising the eyes comprising a frame member defining a trackway, stop members at each end of the trackway, an object longitudinally movable on said trackway and limited in its outward movements by said stop members, said object being movable upon tilting of the trackway and means mounted on the frame 25 member for contacting a portion of the body for holding the device spaced a predetermined distance from the eyes.

HUGO BERMANN.
